CLAIM

The ornamental design for a combined attache case and travelling desk, as shown and described.

DESCRIPTION

FIG. 1 is a perspective view of a combined attache case and travelling desk showing my new design in a closed vertical position.

FIG. 2 is a perspective view of the combined attache case and travelling desk shown in FIG. 1, in an horizontal position with a central storage compartment thereof opened.

FIG. 3 is a front perspective view of the combined attache case and travelling desk with the travelling desk compartment and the central storage compartment shown in open position; and

FIG. 4 is a rear perspective view of the combined attache case and travelling desk showing the top, bottom, and back side thereof.

FIG-1-

FIG-2-
